UNITED STATES PATENT OFFICE.

WILLIAM L. CONNOLY, OF NEW YORK, N. Y.

CANDELABRUM.

1,204,134.

Specification of Letters Patent.

Patented Nov. 7, 1916.

Application filed April 21, 1914, Serial No. 833,512. Renewed September 29, 1916. Serial No. 122,930.

To all whom it may concern:

Be it known that I, WILLIAM L. CONNOLY, a citizen of the United States, and a resident of New York, county and State 5 of New York, have invented a certain new and useful Improvement in Candelabrum, of which the following is a full, clear, and exact specification.

This invention relates to a class of can-10 delabrum adapted to be used for supporting burning candles.

My invention has for its object primarily to provide a candelabrum having separable parts to permit it to be packed into a compact parcel so as to be conveniently carried by a person or easily transported whereby 15 candles may be supported when lighted for use at biers and elsewhere, and wherein are provided foldable supporting members on 20 which are mounted rows of cups for holding the candles, the supporting arms and the cups being relatively arranged in the form of a cross disposed on an incline so that the lights of the candles will appear in 25 similar formation.

Another object of the invention is to provide a standard composed of two extensible members, and on one of these members is detachably mounted the supporting arms so 30 as to be adjusted to suitable heights; and still another object of the invention is to provide a base, or bracket adapted to be detachably applied to the extensible standard whereby the standard and the cross-shaped 35 arms may be properly supported.

A further object of the invention is to provide a form of candelabrum which may be made in any desired size in plain or highly ornamental designs.

40 A practical embodiment of the invention is represented in the accompanying drawing forming a part of this specification in which similar characters of reference indicate corresponding parts in all the views, 45 the said invention being more fully described hereinafter, and then pointed out in the claim at the end of the description.

In the drawing, Figure 1 is a perspective view of one form of candelabrum embodying 50 my invention. Fig. 2 is an elevation of the rod of the standard of the candelabrum. Fig. 3 is an elevation of the recessed post of the standard, and Fig. 4 is an elevation of the foldable bracket employed in the can-55 delabrum.

The candelabrum has a foldable candle

supporting member 10 which is in the form of a cross whereby a lower arm 11, an integral upper arm 12, and two oppositely extending transverse arms 13 and 14 are provided. All of the arms of the supporting member may be of any suitable shapes, though these arms are preferably flat, as shown. The transverse arms 13 and 14 are hinged, at 16 and 17, to the opposite edges of the lower part of the upper arm 12 so that all of the arms will be on the same relative plane as well as permitting the transverse arms to be swung alongside of the upper arms, and these transverse arms are of similar lengths to the upper arm of the cross-shaped member.

The cross-shaped member 10 is disposed on an incline, and projecting downwardly from the underside of the arm 11 thereof is a vertically disposed boss 18 having a threaded recess 19 in its free end. Mounted on the upper surface of all of the arms of the supporting member 10 are two rows of spaced cups, as 20 and 21, each of which is adapted to removably hold a candle. Any suitable number of the cups may be employed, and the rows of the cups are arranged in the form of a cross corresponding to the shape of the supporting member 85 so that the candles when lighted will appear in a similar cross-shaped formation disposed on an incline. While in the drawing I show a form of the candelabrum wherein two rows of cups arranged in the 90 shape of a cross are used, it will be understood that forms of the cross-shaped supporting member may be made so that any desired number of rows of cups may be employed.

Serving to permit the supporting member 10 to be raised or lowered to suitable heights, a standard, as 22, is provided, and this standard is composed of two extensible members 23 and 24. The member 23 is in the form of a post having a recess 25 in its upper part, and in the upper part of the post is a threaded opening 26 which communicates with the recess 25. In the threaded opening 26 is a thumb screw, as 27. The member 24 is in the form of a rod which is movably inserted in the recess 25, and the upper part of this rod is threaded so as to be screwed in the recess 19 of the boss 18 of the supporting member 10 for detachably connecting these parts together. To raise 105 or lower the supporting member to a de- 110

sired height, the member, or rod 24 is accordingly adjusted in the member, or post 23 after the thumb screw 27 has been loosened. By then tightening the thumb screw 5 the rod 24 will be held against movement in the post.

In order to properly support the standard 22, I provide a foldable base, or bracket, 10 as 28. The foldable bracket 28 has a ring, or band 29 which is of a diameter to adapt it to be freely guided over the post 23 of the standard 22, and through this ring is a threaded opening 30 in which is passed a thumb screw 31. Extending in lateral directions at spaced intervals from the ring 29 are pairs of lugs, or ears 32, and each pair of the lugs have transverse registered openings in which is held a pin, or pintle 33. The pairs of the lugs 32 are triangularly disposed relatively to the axial center of the ring, and on the pintles 33 between the pairs of the lugs are rotatably held the upper ends of legs, as 34, 35, 36. The legs 34, 35, 36 may be of any desired shapes and 25 lengths, and on the lower end of each leg is provided a foot, as 37. By pivoting the legs 34, 35, 36 in this manner to the ring 29 the legs may be directed inwardly and outwardly with respect to each other. To 30 properly support the standard 22 and the supporting member 10 when the candelabra are in use the ring 29 is guided over the post 22, and by tightening the thumb screw 31 it will engage the post for removably 35 securing the bracket 28 thereto. The legs 34, 35, 36 are then swung in outward diverging directions from the standard, as shown, and to limit the outward movement 40 of the legs the upper ends thereof are bent inwardly toward the ring to provide vertical edges which serve as stops 38 adapted to movably engage the ring when the legs

are thus positioned. In order to separate the parts of the candelabrum when not in use so as to be packed in a compact parcel 45 to enable it to be conveniently carried by a person, or transported, the bracket 28 is detached from the standard 22 by removing the ring 29 therefrom from the standard after the thumb screw 31 is loosened. The supporting member 10 is unscrewed from the rod 24, and this rod is then lowered in the recess of the post 23.

In the foregoing description, I have embodied the preferred form of my invention, 55 but I do not wish to be understood as limiting myself thereto, as I am aware that modifications may be made therein without departing from the principle or sacrificing any of the advantages of this invention, 60 therefore I reserve to myself the right to make such changes as fairly fall within the scope of the appended claim.

Having thus described my invention, I claim as new and desire to secure by Letters 65 Patent:—

A candelabrum comprising, in combination, a member in the form of a cross with its transverse arms hinged to opposite parts of the longitudinal arm so as to be relatively 70 swung to and from right-angular positions, a boss on the underside of the member having a recess, a standard with a recessed member having therein an extensibly movable second member with a threaded end 75 screwed in the recess of the boss, and a supporting bracket removably mounted on the recessed member of the standard.

This specification signed and witnessed this twentieth day of April, A. D. 1914. 80

WILLIAM L. CONNOLLY.
